(57) **CLAIM**

The ornamental design for a plumbing fitting, as shown and
described.

DESCRIPTION

FIG. 1 is a right, top, front perspective view of a plumbing
fitting according to my new design in the form of a handle,
shown with one exemplary escutcheon environment;

FIG. 2 is a front elevational view thereof;

FIG. 3 is a right side elevational view thereof, the left side
elevational view thereof being a mirror image of the right side
shown;

FIG. 4 is a top plan view thereof;

FIG. 5 is a bottom plan view thereof;

FIG. 6 is a rear elevational view thereof;

FIG. 7 is a right, top, front perspective view of a plumbing
fitting according to my new design in the form of a handle,
shown with another exemplary escutcheon environment;

FIG. 8 is a front elevational view thereof;

FIG. 9 is a right side elevational view thereof, the left side
elevational view thereof being a mirror image of the right side
shown;

FIG. 10 is a top plan view thereof; and,

FIG. 11 is a bottom plan view thereof.

The broken line representations in the figures are for the
purpose of illustration only, and form no part of the claimed
design.

In a preferred embodiment, the nature of this product is a
plumbing fitting, such as a handle for a shower and/or bath
control.
